UNITED STATES PATENT OFFICE.

HAROLD D. VASSELIN, OF FITCHBURG, MASSACHUSETTS, ASSIGNOR TO FITCHBURG PATTERN MODEL CO., OF FITCHBURG, MASSACHUSETTS, A COPARTNERSHIP COMPOSED OF CARL P. JOHNSON AND LESLIE A. HAMEL.

BOBBIN SEPARATOR AND FEEDING MACHINE.

Application filed November 14, 1921. Serial No. 514,885.

To all whom it may concern:

Be it known that I, HAROLD D. VASSELIN, a citizen of the United States, residing at Fitchburg, in the county of Worcester and State of Massachusetts, have invented certain new and useful Improvements in Bobbin Separator and Feeding Machines, of which the following is a specification.

This invention relates to the cotton industry and particularly to the cleaning of bobbins used therein and its object is to provide means for taking bobbins from a hopper and delivering them, one after another, head foremost, into a stripping machine, which object is accomplished at present by hand.

The invention is illustrated by the accompanying drawings, in which:

Fig. 1 is a side elevation of the machine with the sides of the hopper removed;

Fig. 2 is a rear elevation of the machine;

Fig. 3 is an elevation looking rearwardly from the line 3—3 Fig. 1;

Fig. 4 is a detail view of a portion of the machine; and

Fig. 5 is a side view of Fig. 4.

The frame of the machine is composed of angle iron members 1 fastened together by sheet iron plates 2; the hopper 6 is attached to cross pieces 11 bolted to the frame, the rear wall of the hopper being formed by the endless chain, or series, of equally spaced conveyors 7 affixed to the outer face of sprocket chain 8 which runs, rearwardly inclined, over sprocket wheels 9, 9^a fixed to shafts 4 journaled in bearings 5 bolted to the frame, said sprocket chain 8 being supported by strips 10 fastened to said cross pieces 11.

Shelf 16, preferably made of wood, is secured to side pieces 28 fastened to guide piece 20 projected from chutes 25 and has its lower end furnished with a knife edge 24 which is disposed adjacent sand roll 19 (adapted to break off loose threads) which is detachably mounted on the frame and serves to prevent bunching of waste on said roll.

Chutes 25, supported by cross pieces 29 attached to the frame, are angularly disposed and lead downwardly to chutes 26 angularly disposed below them with their upper ends attached to brackets 30 secured to pieces 31 affixed to the frame and with

their lower ends secured to sides 32 of reservoirs 27, 27^a, from which, respectively, are projected brackets 33, 33^a; there being hinged to brackets 33 at 35 swinging members 34 which form the backs of reservoirs 27; and there being rigidly attached to bracket 33^a member 34^a which forms the back of reservoir 27^a.

A second endless sprocket chain 38, disposed rearwardly of and preferably at a slightly steeper incline than sprocket chain 8, runs over sprocket wheels 39, 39^a fixed to shafts 4^a journaled in bearings 5^a bolted to the frame; said sprocket chain 38 being supported by strips 48, which are supported in turn by cross pieces 47 affixed to the frame; and there being attached to the outer face of said sprocket chain 48 an endless chain, or series, of equally spaced conveyors 37.

Chutes 25, 26 are furnished with canvas coverings (not shown) for the purpose of confining the bobbins therein.

Pivoted bars 17, adapted to swing upwardly, are hinged to cross pieces 18 disposed on sides of hopper 6 and normally extend inwardly approximately to and at right angles to the outer ends of the opposite conveyors 7; these bars 17 prevent backward movement of the bobbins. Angular guide 44 (Figs. 4 and 5) and wedge-shaped guides 45 are secured to return chute 46 which is attached to cross pieces 47 affixed to the frame and leads to receptacle 49. Adjusting attachments 50 are also affixed to reservoir side 32.

The conveyors 37 are so formed and spaced as to carry, each, a single bobbin lying horizontally therein; a bobbin 43 (Fig. 4) that extends out over the edge of the conveyor is forced back into proper position therein by angular guide 44, which operation is assisted by the rounded edge of the conveyor; or, if extending out too far for control by guide 44, the bobbin is forced out of the conveyor by wedge-shaped guide 45, into chute 46 which conducts the bobbins thrown into it and also surplus bobbins in reservoirs 27 to receptacle 49. Bobbins that are shorter than the length of the conveyor are adjusted by attachment 50.

Where two bobbins 51 (Fig. 4), shorter than the length of the conveyor, occupy the same conveyor, lying therein with their heads in opposite directions, attachment

50 with its wedge-shaped edge engages the head of the bobbin adjacent thereto and forces said bobbin over and, owing to the slope of the conveyor, one bobbin drops 5 back.

A bobbin 53 (Fig. 2) reaching the top of the endless rearward carrier lies in a horizontal position in its conveyor and, as its head, which is the end largest in diameter, rolls out of the conveyor first, assumes a vertical headdownward position and drops headforemost into the funnel-shaped cylinder 36 supported by brackets 32 attached to the frame.

15. The driving mechanism comprises the following: Drive pulley 23 mounted on the frame; cross belt 22 driven thereby and driving pulley 21 affixed to shaft of sand roll 19; sprocket wheel 14 affixed to main 20 shaft (drive pulley shaft) and driving sprocket chain 18, driving sprocket wheel 12 fixedly mounted on shaft 4, driving sprocket wheel 9, driving sprocket chain 8; sprocket chain 38, driven by sprocket wheel 39, driven by sprocket wheel 40, driven by sprocket chain 41, driven by sprocket wheel 42, fixedly mounted on shaft 4.

The operation of the machine is as follows: The bobbins which are to be cleaned 30 are deposited in hopper 6 and are there kept in motion by the moving rearward wall of the hopper and gradually separated and conveyed by conveyors 7 up over sprocket wheels 9 and dropped onto shelf 35 16, down which they slide to and over sand roll 19, which revolves at a high rate of speed and breaks off any dangling waste as the bobbin passes over it, and thence from the sand roll along the guide 40 piece 20 into chutes 25, thence into chutes 26, thence into reservoirs 27, 27^a, where they are picked up individually one after another by conveyors 37 which carry them up over sprocket wheels 39 and drop them 45 headforemost into funnel 36, whence they fall headforemost into the stripping machine (not shown).

A vacuum system may be employed for preventing bunching of waste on the sand 50 roll.

I claim:

1. A machine for picking up bobbins and dropping them headforemost from a predetermined height comprising two endless carriers arranged one behind the other and inclined upwardly and rearwardly; a hopper disposed adjacent the lower end of the front carrier and having as one of its walls the traveling front of said carrier; a knife-edged, downwardly-inclined shelf disposed 60 behind and below the top of the front carrier; a sand roll disposed adjacent the lower end of the shelf; chutes angularly disposed below the sand roll; reservoirs disposed below the chutes and adjacent the lower front end of the rear carrier; means disposed adjacent the front and sides of the carriers for guiding the bobbins, each, into a horizontal position in its carrier; and means for driving the carriers in the same direction and the sand roll in the opposite direction.

2. A machine for picking up bobbins and dropping them headforemost from a predetermined height comprising two endless carriers arranged one behind the other and inclined upwardly and rearwardly; stripping mechanism disposed rearwardly and below the top of the front carrier; chutes angularly disposed below the stripping mechanism; reservoirs disposed below the chutes and adjacent the lower front end of the rear carrier; and means for driving the carriers in the same direction.

3. A machine for picking up bobbins and dropping them headforemost from a predetermined height comprising two endless carriers arranged one behind the other and inclined upwardly and rearwardly; stripping mechanism disposed rearwardly and below the top of the front carrier; chutes angularly disposed below the stripping mechanism; reservoirs disposed below the chutes and adjacent the lower front end of the rear carrier; means disposed adjacent the carriers for guiding the bobbins into proper position in the conveyors; and means for driving the carriers in the same direction.

HAROLD V. VAGSELEN.
